UNITED STATES PATENT OFFICE.

WILLIAM F. FELTEN, OF MERRILL, WISCONSIN, ASSIGNOR OF ONE-HALF TO
ARMENIGLE BERNIER, OF SAME PLACE.

DRIVE-WELL POINT.

SPECIFICATION forming part of Letters Patent No. 352,531, dated November 16, 1886.

Application filed May 26, 1886. Serial No. 203,302. (No model.)

To all whom it may concern:

Be it known that I, WILLIAM F. FELTEN, a citizen of the United States, residing at Merrill, in the county of Lincoln and State of Wisconsin, have invented certain new and useful Improvements in Drive-Well Points; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to that class of drive-well points having surrounding strainers, and has for its object to provide a guard for the same to prevent injury when being driven through strata of rock.

20 It consists in the novel features more particularly hereinafter set forth and claimed, and shown in the annexed drawings, in which—

Figure 1 is a view in elevation of a point of my construction embodying my invention. 25 Fig. 2 is a section on the line xx of Fig. 1. Fig. 3 is a view in elevation, parts being broken away, showing the details of construction and relative location of the parts.

The device comprises the short tube A, having a series of perforations, A', arranged in parallel rows, strainers B and C, the former of wire-gauze, the latter of foraminous metal, the steel-point D, and the guards E, which are arranged between the rows of perforations, and held in place by screws e, passing through the screens and into the tube. The screws are countersunk in the guards, so as to come flush with the guards, and not present any projecting points, which would impede the advance of the point when driving.

The guards consist of metal bars, and may be of any desired length, and of any shape in cross-section. They are of sufficient thickness, and arranged in such proximity to each other that they form a complete barrier and ward off stones, &c., and prevent injury to the strainers when the well is being driven.

The base of the point bulges and projects beyond the sides of the tube to give clearance for the guards, the ends of which taper to assist in gently pushing aside any unyielding substance. The outer screen is longer than the inner one, and its ends are bent thereover and soldered to the tube.

Having thus described my invention, what I claim, and desire to secure by Letters Patent, is—

The herein shown and described well-point, consisting of the following elements: the tube A, having a series of perforations longitudinally arranged in parallel rows; surrounding screens, bars located opposite the spaces between the rows of perforations, and serving the double purpose of clamping the screens between them and the tube, and a barrier or guard for preventing injury to the screens, screws passed through the bars and screens and screwed into the tube for retaining the bars in place, and a point secured to the lower end of the tube, and having its base bulging and extended beyond the sides of said tube, substantially as shown, and for the purposes described.

In testimony whereof I affix my signature in presence of two witnesses.

WILLIAM F. FELTEN.
